UNITED STATES PATENT OFFICE

2,417,277

RESONATOR FOR MUSICAL INSTRUMENTS

Archie M. Tyson, Dallas, Tex.

Application November 17, 1944, Serial No. 563,884

3 Claims. (Cl. 84—189)

1

This invention relates to a resonator for musical instruments and while it is designed primarily for installation in pianos, it is to be understood that it can be employed to advantage in connection with any type of stringed instrument.

The invention is designed primarily as an improvement upon the structure disclosed in Patent 2,287,503, issued to me on June 23, 1942.

The invention has for its primary object the utilization of a vibratory element suspended in a new and novel manner whereby the resonance of the instrument is improved and the period of vibration prolonged so that the tone produced is not only more sustained but also more pleasing in sound than generally possible heretofore.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a section through a portion of a piano showing the present improvements combined therewith.

Figure 2 is a bottom plan view of the resonator.

Figure 3 is a horizontal section through a portion of a sounding board to which a modified form of resonator is applied, said resonator being shown in plan.

Figure 4 is an elevation of a portion of a sounding board bridge to which a resonator is applied.

Figure 5 is a top plan view of the resonator and a portion of the bridge shown in Fig. 4, the adjacent portion of the sounding board being in section.

Referring to the figures by characters of reference, 1 designates a portion of a sounding board to which a rib 2 is joined in the usual manner. A stem 3 abuts at one end against the rib and is held firmly thereto by any suitable means, such as a screw 4.

A stanchion of the piano is indicated in part at 5 and has a block 6 attached to it. This block is designed to support the resonator which, as shown, comprises a single length of wood reduced in thickness at an intermediate point to provide a neck 7, an attaching end 8, and an elongated tongue 9. The end 8 is held rigidly to the block 6 by screws 10 or the like so that the resonator

2

thus is held normally in a position substantially parallel with the sounding board. When in its normal position, that end of the tongue 9 nearest the neck 7 is in contact with the stem 3 and is held tightly thereto by the screw 4 heretofore mentioned. The other end portion of the tongue 9 carries a weight 11 which can be in the form of a metal plug seated within the tongue.

A longitudinal slot 12 is formed in the tongue 9 and suspended within this slot is a coiled spring 13 one end of which is engaged by the screw 4 while the other end is fastened to the tongue by a screw 14 or the like. This spring has its convolutions out of contact with the tongue and constitutes the resonant element of the device.

When the resonator is properly installed the spring is under tension and the tongue 9 is in firm contact with the stem 3. Vibration of the strings of the instrument results in transmission of the vibration from the sounding board through the rib 2 and stem 3 to the tongue 9 with the result that the tensioned spring is also vibrated and a resonance created which sustains and otherwise improves the tone quality of the instrument.

It is important that the spring-carrying member be fixedly joined to the sounding board so that it will have no movement at its point of connection therewith other than the motion or vibration transmitted thereto by the stem 3. By reducing the thickness of the structure to produce the neck 7, the vibration of the tongue 9 and the supported spring is not retarded. Furthermore by supporting the resonator as described, it exerts no pressure against the sounding board and, therefore, does not tend to dampen the tone produced.

While the structure thus far described and as shown in Figures 1 and 2 shows the resonator mounted on a supporting means separate from the sounding board, it is to be understood that it can be mounted directly on the sounding board as shown for example in Figs. 3, 4 and 5. By referring to Fig. 3 a block 15 is secured directly to the rib 16 of the sounding board 17. The resonator 18 is secured to this block in the same manner as is the one thus far described and it is likewise provided with an intermediate neck 19, a weight 20, and a spring 21 all positioned and operating as disclosed in connection with Figs. 1 and 2.

It has also been found in practice that under some conditions it may be desirable to mount the resonator on the bass bridge of the piano. In Figs. 4 and 5 a portion of the bass bridge has 55 been shown at 22, the same being secured in the

usual manner to a sounding board 23. The resonator is attached at one end to this bridge by means of screws 24 or the like and if desired spacing elements 25 may be interposed between the resonator and the bridge. In other respects the resonator shown in Fig. 5 is the same as the one shown in Figs. 1 to 3 inclusive, the attached end 26 being spaced from a slotted end portion 27 by a neck 28 and a spring 29 being stretched longitudinally of the slot 30, as illustrated in Fig. 4. A weight 31 is also provided adjacent to the free end of the resonator.

In practice the resonators shown in Figs. 3, 4 and 5 all act in the same advantageous manner as do the forms shown in Figs. 1 and 2.

In Figs. 4 and 5 the strings joined to the bass bridge have been indicated at 32.

What is claimed is:

1. A resonator for the sounding board of a musical instrument including an elongated element having a freely supported end, means for fixedly joining the other end to a sounding board, an intermediate portion of said element being reduced in thickness to provide a neck, and a tensioned coiled spring carried by the free end portion of the element and having its convolutions spaced from said element.
2. A resonator for the sounding board of a musical instrument including an elongated vibratory element having a reduced intermediate portion, means for fixedly connecting said ele-

ment to a sounding board at one side of the reduced intermediate portion, and a constantly tensioned coiled spring carried by the other end portion of said element and positioned with its convolutions spaced from the element.

3. A resonator for the sounding board of a musical instrument including an elongated vibratory element having a reduced intermediate portion, means for fixedly connecting said element to a sounding board at one side of the reduced intermediate portion, a constantly tensioned coiled spring carried by the other end portion of said element and positioned with its convolutions spaced from the element, and a weight carried by the free end portion of the element.
